REMOVABLE SHAVING-HOOD UNIT OF A DRY-SHAVING APPARATUS

The invention relates to a removable shaving-hood unit for a dry-shaving apparatus comprising at least one shaving head and a surrounding circumferential skin-tightening member which is vertically adjustable relative to the shaving head.

A vertically adjustable tightening rim is described in U.S. Pat. No. 2,223,286. In this known apparatus, the tightening-rim height to be used is adjustable by turning the rim. Such turning of the tightening rim has the disadvantage that during use a height adjustment is hardly possible, because such a turning movement causes the skin to bulge.

It is an object of the invention to eliminate this disadvantage, and the invention is characterized in that the skin tightening member, which is arranged so as to be locked against rotation, is maintained in engagement with a separate height-adjusting member by spring force.

The invention is further characterized in that the skin tightening member and a plate-shaped shaving head support, which carries the shaving head or heads, are interconnected by springs disposed between them and are arranged so as to be capable of sliding movement relative to one another; in the mounting position of the shaving-hood unit the plate-shaped shaving head support is maintained in resilient engagement with a vertically protruding rim of the apparatus casing by these springs. This construction provides the advantage that the shear plate support may be mounted on the apparatus casing without further securing means.

An embodiment of the invention is characterized in that the sleeve-shaped skin-tightening member has the form of the substantially conical surface of a truncated cone, the upper end of which is vertically flanged over inwardly; the rounded junction between the flange and the conical surface skin-tightening rim, and an annular lower end which, in the mounted position of the shaving hood unit, resiliently engages the upper surface of an annular abutment which is rotatably supported in the apparatus casing and is vertically adjustable.

In this embodiment, the vertically adjustable annular abutment is spaced from the skin-tightening rim by a distance such that even during shaving a further refinement of the vertical adjustment of the skin-tightening rim is readily obtainable.

An advantageous embodiment is characterized in that the inner surface of the sleeve-shaped skin-tightening member is formed with at least one, and preferably three, inwardly projecting vertically extending rib or ribs, which fit in slots formed in the protruding rim of the apparatus casing on which the shaving head support rests. Each rib has a notch formed in it, the lower downwardly inclined wall of which constitutes a contact face for the end of an arm of a pivoting lever mounted in the apparatus casing so as to be pivotable in a vertical plane; this arm is supported by a spring arranged in the apparatus casing. The construction of this embodiment provides a possible manner of holding the shaving head unit against the apparatus casing by spring force.

This embodiment is further characterized in that the other arm of the pivoting lever is radially displaceable by means of a disc which is rotatable in a plane substantially parallel to the shaving head support. This disc is provided at its circumference with at least one substan-

tially tangentially curved outline inclined towards the disc-center rotation in the direction in accordance with the inclination of this curved outline, displaces the other arm in a radial direction, with the result that the 5 resiliently supported arm of the lever is entirely disengaged from the notch in the respective rib, so that the shaving hood unit is detachable, and this rotation of the disc may be effectuated by means of a lug which is connected to it and protrudes from the apparatus casing.

10 According to this construction the shaving hood unit may readily be removed from the apparatus casing, while nevertheless a firm connection between the unit and the casing is obtainable. Furthermore, this construction is eminently suitable for manufacture by mass 15 production methods. The resilient connection between the skin tightening member and the plate-shaped shaving head support may be achieved by an embodiment which is characterized in that each rib which is provided on the inner wall of the sleeve-shaped skin-tightening member and protrudes inwardly, is provided near its upper end with a preferably rectangular recess in which the body of a substantially U-shaped spring is freely movable in a vertical direction; the limbs of this 20 spring project upward along both sides of the rib and extensions of these limbs (bent over outwardly at right angles) pass through slots formed in lugs which are located on both sides of the rib and project from the plate-shaped shaving head support; These extensions then terminate in mutually diverging upwardly protruding further extensions the free ends of which resiliently 25 engage the inner wall of the transverse end of the skin tightening member. Here also a simple construction is used which effectuates the said resilient connection.

30

The invention will be described more fully with reference to drawings of an embodiment, in the description of which further advantageous details will become manifest.

BRIEF DESCRIPTION OF THE DRAWINGS

FIG. 1 is a side elevation, partly in section, the sectional view taken along line I—I of FIG. 2, of a shaving hood unit secured to the dry-shaving apparatus.

FIG. 2 is a top plan view of the shaving hood unit, which is partly broken away, and

FIG. 3 is a fragmentary side elevation view thereof.

THE PREFERRED EMBODIMENT

The shaving hood unit according to the invention comprises a tightening member 1 and a plate-shaped shaving head support 2. The shaving head support 2 carries three shaving heads 4, one of which is shown in FIG. 1 and two of which are shown in FIG. 2. The tightening member, which is sleeve-shaped, has the form of a substantially conical surface of a truncated cone, the upper rim of which is vertically bent over inwardly; the rounded junction between the flange 5 and the sleeve 6 form a tightening rim 7. The lower end 8 of the tightening member 1 is annular. In the mounted position of the shaving hood unit the tightening member rests upon an annular abutment 9. The inner wall of the sleeve-shaped tightening member 1 is provided with at least one vertically extending rib 10. This rib 10, which fits in a slot 34 in a vertically protruding rim 35 of the apparatus casing on which the shaving head support 2 rests, is provided with a notch 11 the lower downwardly inclined sidewall 12 of which forms a contact surface for an end 13 of an arm of a pivoting lever 14 which is

mounted in the apparatus housing so as to be pivotable in a vertical plane. The end 13 of the arm 15 of this pivoting lever 14 engages the sidewall 12 of the notch 11. Arm 15 is resiliently supported by a spring 16 mounted in the apparatus casing, which spring preferably is in the form of a wire spring. The other arm 36 of the pivoting lever 14 is radially displaceable by means of a disc 17 which is arranged for rotation in a transverse plane about an axis arranged centrally of the apparatus casing. This disc 17 is provided at its circumference with at least one curved edge 18 which is a cam that engages the end of the arm 36. During a rotation of the disc 17, the curved edge 18 thereof displaces the arm 36 of the pivoting lever 14 with the initial result that the resiliently supported arm 15 of the pivoting lever 14 is completely disengaged from the notch 11 formed in the rib 10. In such a situation the other end 8 of the tightening member is no longer maintained in resilient engagement with the annular abutment 9 so that the shaving hood unit may be removed.

At its upper end the rib 10 has a preferably rectangular recess 19 formed in it; a body 20 of a substantially U-shaped spring 21 is freely movable vertically (see FIG. 3) in recess 19. The two limbs 22 of the spring 21 project upwardly each along one side of the rib 10. Outwardly bent extensions 23 of the limbs 22 pass through slots 24 in lugs 25 which are located on both sides of the rib 10 and protrude from the plate-shaped shaving head support 2, while after these extensions 23 have passed through the slots 24 they terminate in diverging upwardly projecting further extensions 26, the free ends of which resiliently engage the inner wall of the abutment rim 7.

The extensions 26 of the spring 21 press the plate-shaped shaving-head support 2 down against the vertically protruding rim 35, while in the vertical adjustment of the tightening member 1 the body 20 of this spring is vertically movable in the recess 19 in the rib 11. This construction ensures that in any position of the tightening rim 7 the shear plate holder is maintained in resilient engagement with the rim 35 of the apparatus casing. The annular abutment 9 is shaped substantially in the form of an inverted U in a cross-section taken through the axis of the annulus. The inner wall 27 of this abutment has recesses 28 formed in it, the largest dimensions of which are smaller than the diameter of a ball 29 which is resiliently pressed against this inner wall 27 by a spring 30 mounted in the apparatus casing. When the abutment 9 is rotated, the ball 29 is urged into the next notch 28 each time in a direction opposite to the rotation of the abutment 9. This displacement of the ball 29 makes a clicking sound so that the user's attention is drawn to the fact that a different adjusting height is obtained. Thus, starting from a zero position he only has to ascertain the number of clicks required to produce that adjusted position of the tightening member which is most suitable for him. The obtaining of this adjusted position is further facilitated in that the annular abutment at its outer wall 31 is provided with a projection which in the lowermost position of the tightening member registers with a digit zero indicated on a cover plate of the apparatus casing. This cover plate of the apparatus casing is not shown in the Figures. Successive digits on this cover plate indicate the extent to which the tightening member is vertically adjusted. The annular tightening member rests on a support 32 which is at a level relative to the apparatus

casing which is not the same at all points, while the body of the abutment 9 is of varying thickness. The effect of this construction serves to render the annular abutment vertically adjustable as regards its upper surface; this may be achieved alternatively by giving the support a level or height relative to the apparatus casing, which is not the same at all points. In the embodiment shown in the drawings, the shaving-hood unit comprises two plates, the outwardly flanged walls of the hood-shaped shear plates of the shaving heads 4 being vertically movable between the said plates. The form of the plate-shaped shaving-head support 2 of the embodiment shown is triangular with rounded corners. The rotary disc 17 is provided with a lug 33 which protrudes from the shaving-hood unit and by means of which the disc may be rotated.

Obviously, the invention is not restricted to the above description of an embodiment. Several alternative embodiments having the same effect are possible. The embodiment described, however, has the advantage that its component parts are simple and, as practice has shown, may readily be manufactured by mass production methods.

What is claimed is:

1. In a dry shaver including a generally cylindrical casing which when upright has a vertical axis, a top end, side walls, and axially spaced below said top end a generally annular support part, a shaving hood unit comprising a top plate carrying at least one shaving head which plate and shaving head are positionable at a predetermined elevation relative to said casing, a sleeve having a bottom part, and a top end formed as a rim that circumscribes said plate, the sleeve and plate resiliently secured together, means for releasably securing said sleeve to said casing coaxially therewith, first resilient means urging said sleeve axially downward relative to said casing, means for variably moving the sleeve upward relative to the casing while the plate is maintained at said predetermined elevation, such that said rim of the sleeve is positionable at varying elevations equal with and above said plate.

2. Apparatus according to claim 1 wherein said means for variably moving the sleeve upward comprises an inclined cam surface on the top of said annular support part of said casing, the cam having parts of lower and higher elevations, a follower positioned in between and engaging said cam surface and the bottom parts of said sleeve, said follower being movable on said cam, which thereby drives said sleeve to corresponding elevations.

3. Apparatus according to claim 2 wherein said follower is a ring that circumscribes said casing while contacting said annular support part thereof.

4. Apparatus according to claim 1 wherein said sleeve is a truncated cone.

5. Apparatus according to claim 1 wherein said means for releasably securing the sleeve to said casing comprises at least one first lever pivotally mounted on said casing, the lever having a top arm engagable to said sleeve and a bottom arm, second resilient means urging said lever to be pivoted so the top arm engages said sleeve and urges same downward, drive means movably mounted to said casing for engaging said bottom arm of the lever and pivoting the lever such that the top arm thereof is disengaged from said sleeve, and consequently the sleeve and top plate are removable from the casing.

6. Apparatus according to claim 5 wherein said lever pivots in a generally vertical plane with the upper arm movable radially outward and inward, and said drive means is a second lever movable about said casing axis.

7. Apparatus according to claim 5 wherein said sleeve defines a wall with an inside surface with a notch in said surface into which said first lever's top arm is extendible.

8. Apparatus according to claim 1 further comprising two additional shaver heads in said plate symmetrically spaced about said casing axis.

9. Apparatus according to claim 5 further comprising

two additional first levers symmetrically spaced about said casing axis.

10. Apparatus according to claim 1 further comprising means for fixing the minimum distance between the top of said casing and said top plate and shaving head while said first resilient means urges said sleeve and plate attached thereto downward, and third resilient means urging the plate downward relative to the top of the sleeve, the first resilient means having a greater spring constant than the third resilient means.
